UNITED STATES PATENT OFFICE

152,487

DESIGN FOR A SPECTACLE FRAME

Aurel E. Mangold, New York, N. Y.

Application April 12, 1946, Serial No. 128,557

Term of patent 14 years

(Cl. D57—1)

To all whom it may concern:

Be it known that I, Aurel E. Mangold, a citizen of the United States, residing at New York, in the county and State of New York, have invented a new, original, and ornamental Design for a Spectacle Frame, of which the following is a specification, reference being had to the accompanying drawing, forming part thereof.

Fig. 1 is a perspective view; and

Fig. 2 is a top plan view of a spectacle frame, showing my new design.

The dominant feature of this design is the studs having decorative, slightly flattened heads and distributed around the spectacle frame.

I claim:

The ornamental design for a spectacle frame, as shown and described.

AUREL E. MANGOLD.
